TORSION SET ROTARY JAR

James Allen Kammerdiner, Los Angeles, Calif.

Application October 29, 1932, Serial No. 640,139

7 Claims. (Cl. 255—27)

This invention relates to a rotary jar for use in fishing operations, jarring tools or the like in well holes. It appertains more particularly to a jar having two sections connected for limited longitudinal movement and having trip means to restrain the sections against longitudinal movement at one end of their travel and arresting means to limit longitudinal movement at the other end of their travel and effect a jarring action. The trip means is characterized by being releasable by an angular movement of the sections. Such jarring tools employing an upward blow depend for efficient action upon the elastic stretch of the drill pipe which acts as resilient means to produce an impact of great magnitude. In a downward drive, they depend upon the accumulation of the load of the drill pipe and associated parts supported thereon. Such metallic drill pipe has torsional elasticity and the trip means may be restrained against release by exerting a torsional stress to counteract the torsional component of a longitudinally exerted stress. The present invention has for its object the provision of a jar relying upon selected torsional and longitudinal stresses for tripping. It is apparent that if the pitch of the threads on the shell and mandrel of the rotary jar of the type disclosed in U. S. Patent #1,672,321, granted to me June 5, 1928, is made great enough, the jar may be operated by taking advantage of the relation of torsional stress to longitudinal stress as hereinbefore described. However, in practice the threads would be pitched in the opposite direction to avoid unscrewing of the joints between sections of the drill pipe. When the jar is so constructed and used, due to the large area of frictional contact, the reactions to release of the trip members depends not only upon the torsional resiliency but also upon the resistance to sliding of the frictionally engaged surfaces. This varies depending upon grit in the circulating fluid and abrasion of the contacting surfaces due to wear. For the reasons mentioned, it is impossible to accurately govern the intensity of the jarring action by the torsional stress placed on the jar. Furthermore, due to the heavy stresses placed on the trip members excessive wear takes place and the jar after short use requires servicing. Another object of this invention is to provide a jar of the character described which will obviate the last mentioned disadvantages.

These objects are accomplished by means of one embodiment of my invention illustrated in the accompanying drawing in which:—

Fig. 1 is an axial section through a jar in set

position; Figs. 2 and 3 are sections as seen on the lines correspondingly numbered in Fig. 1; Fig. 4 is an enlarged view of a fragment of the jar partly in section and partly in elevation as seen at a right angle to Fig. 1; and Fig. 5 is a sectional view of the fragment of the bowl shown in Fig. 4 looking at a different angle.

Referring with more particularity to the drawing, the jar comprises a bowl A and a mandrel B telescopically engaged therewith. The trip is indicated generally by C.

The bowl comprises a tubular shell 6 internally threaded at its ends. At the lower end an anvil nut 7 is attached being provided with a bore to accommodate travel of the mandrel. At the upper end a head 8 is attached. The head is provided with a chamber 9 of reduced diameter as compared with the bore of the shell. A stuffing box 10 packs a wash pipe secured to the mandrel. The shell 6 is bored and tapped at diametrically opposite points to receive threaded pintles 11 serving as journals for rollers 12. The pintles may be further secured in position and the shell strengthened by welds 13. There are two longitudinally aligned sets of rollers spaced in accordance with tracks on the mandrel. Keys or ribs 14 project from the inner wall of shell 6 below the rollers and there are two ribs diametrically opposite one another. These ribs are of a width to occupy approximately one-eighth of the periphery leaving a space of three-eighths between them.

Disposed within the shell 6 is the mandrel having a hollow stem 15 upon which is a hammer head 16 for coaction with anvil 7. The hammer head 16 and anvil 7 limit expansion of the jar by their engagement. The upper portion 17 of the mandrel forms a plunger to work in chamber 9. A wash pipe 18 is attached to the mandrel and forms a continuation of the bore of the mandrel to provide for circulation through the jar. Relief ducts 19 are provided for chamber 9. On the mandrel are sloping tracks 20 in the nature of interrupted threads. There are two sets of longitudinally aligned tracks, one set being diametrically opposite the other and the tracks in a set being spaced to accommodate the rollers 12. The tracks have a relatively great pitch and each preferably occupies one quarter of the periphery of the bore of the shell. Above tracks 20 are bosses 21 limiting by their side walls engagement with rollers 12 preventing the riding of the rollers onto the tracks until the bosses have passed above the topmost rollers, thereby insuring complete contraction of the jar. On the

mandrel below tracks 20 are ribs or keys 22, each occupying approximately one-eighth of the periphery of the mandrel and leaving three-eighths clearance between them.

5 It will be noted that there is sufficient space between the sets of rollers for the sets of tracks to pass and vice versa. The ribs 14 and 22 form a spline or abutments so proportioned as to permit only a quarter of a turn of the shell in relation to the mandrel; in one extremity of this movement the rollers are fully engaged with the tracks; at the other extremity they are out of engagement and the bowl and mandrel are free for limited longitudinal movement in relation to one another. The spline acts to limit rotary movement of the bowl and mandrel in relation to one another and enables rotation of the drill string of which it forms a part to be transmitted to a tool below the jar. The jar is placed in a 10 string of drill pipe adjacent the lower end, a suitable tool being attached to the lower end of the string. The tool may be rotated by means of the drill string. When it is desired to actuate the jar, the drill string is lowered to effect 15 contraction of the jar sections and then turned, the rollers and tracks engaging. A torsional strain is then maintained on the jar and an upward pull exerted by means of the drill string. The elasticity of the drill string enables energy 20 to be stored in the drill string which is a torsional strain and a tensile strain. The tensile strain through the action of the rollers and track is resolved into components including a torque reactive to the torsional strain and when of sufficient magnitude to overcome the torsional strain 25 will cause the bowl and mandrel to rotate relative to one another and the rollers and track to disengage and release the jar sections. The hammer and anvil are then sprung toward one another to produce a heavy jarring blow. Obviously the energy stored in the drill string and the tensile strain to effect release is directly proportional to the torsional stress exerted. Thus, the magnitude of the impact blow may be governed by the torsional stress. If it is desired to 30 effect a series of jarring blows in rapid succession, the torsional stress is maintained, the drill string being raised and lowered while the trip automatically sets the jar and releases upon 35 sufficient tension being attained.

What I claim is:—

1. A rotary jar consisting of two sections related for limited longitudinal movement, jarring means to arrest longitudinal movement of said sections at one end of the longitudinal travel thereof to effect a jarring action, trip means to interlock said sections at the other end of their longitudinal travel and enable angular movement, said trip means including an inclined engaging surface on one of said sections and a roller journaled on the other section disposed to be abutted therewith in one angular position and thereby restrain longitudinal movement of said sections, said inclined engaging surface being of sufficient pitch for a predetermined longitudinal stress to cause said roller to ride over said surface to another angular position free of said surface for expansive movement of said sections to jarring position, said trip means being maintainable in interlocking relation by a torsional stress against the action of a longitudinal stress exerted upon said sections.

2. A rotary jar consisting of two sections related for limited longitudinal movement, jarring means to arrest longitudinal expansive movement

of said sections to effect a jarring action, trip means to interlock said sections in contracted relation and enable angular movement, said trip means including an inclined engaging surface on one of said sections and a roller journaled on the other sections disposed to be abutted therewith in one angular position and thereby restrain expansive movement of said sections, said inclined engaging surface being of sufficient pitch for a predetermined longitudinal stress to cause said roller to ride over said surface to another angular position free of said surface for expansive movement of said sections to jarring position, said trip means being maintainable in interlocking relation by a torsional stress against the action of a tensile stress exerted upon said sections.

3. A rotary jar comprising a hammer member and an anvil member telescopically connected for limited longitudinal movement, said members being provided with jarring means to arrest longitudinal movement of said members at one end of the longitudinal travel thereof to effect a jarring action, trip means to interlock said sections at the other end of their longitudinal travel and enable angular movement, said trip means including an inclined engaging surface on one of said members and a roller journaled on the other member disposed to be abutted therewith in one angular position and thereby restrain longitudinal movement of said members, said inclined engaging surface being of sufficient pitch for a predetermined longitudinal stress to cause said roller to ride over said surface to another angular position free of said surface for longitudinal movement of said members to jarring position, said trip means being maintainable in interlocking relation by a torsional stress against the action of a longitudinal stress exerted upon said members.

4. A rotary jar comprising a hammer member and an anvil member telescopically connected for limited expansive longitudinal movement, said members being provided with jarring means to arrest longitudinal expansive movement of said members to effect a jarring action, trip means to interlock said sections of contracted relation and enable angular movement, said trip means including an inclined engaging surface on one of said members and a roller journaled on the other member disposed to be abutted therewith in one angular position and thereby restrain expansive movement of said members, said inclined engaging surface being of sufficient pitch for a predetermined longitudinal stress to cause said roller to ride over said surface to another angular position free of said surface for expansive movement of said members to jarring position, said trip means being maintainable in interlocking relation by a torsional stress against the action of a tensile stress exerted upon said members.

5. A rotary jar comprising a bowl member and a mandrel member telescopically connected for limited longitudinal movement, said members being provided with jarring means to arrest longitudinal movement of said members at one end of the longitudinal travel thereof to effect a jarring action, trip means to interlock said members at the other end of their longitudinal travel and enable angular movement, said trip means including an inclined engaging surface on said mandrel member and a roller journaled on said bowl member disposed to be abutted therewith in one angular position and thereby restrain longitudinal movement of said members, said inclined engaging surface being of sufficient pitch for a predetermined longitudinal stress to cause said roller to ride over said surface to another angular position free of said surface for expansive movement of said members to jarring position, said trip means being maintainable in interlocking relation by a torsional stress against the action of a longitudinal stress exerted upon said members.

- 5 mined longitudinal stress to cause said roller to ride over said surface to another angular position free of said surface for longitudinal movement of said members to jarring position, said trip means being maintainable in interlocking relation by a torsional stress against the action of a longitudinal stress exerted upon said members.
6. A rotary jar consisting of a bowl and a mandrel telescopically connected for limited expansive longitudinal movement, jarring means to arrest longitudinal expansive movement of said bowl and mandrel to effect a jarring action, trip means to interlock said bowl and mandrel in contracted relation and enable angular movement, 10 said trip means including an inclined track on said mandrel and an instanding roller journaled on said bowl disposed to be abutted with said track in one angular position and thereby restrain expansive movement of said bowl and 15 mandrel, said inclined engaging surface being of sufficient pitch for a predetermined longitudinal stress to cause said roller to ride over said track to another angular position free thereof for ex- 20
- 5 pensive movement of said bowl and mandrel to jarring position, said trip means being maintainable in interlocking relation by a torsional stress against the action of a tensile stress exerted upon said jar.
7. In a rotary jar of the class described, a mandrel member and a shell member relatively reciprocal and oscillatable with respect to each other and having cooperating impact surfaces, means for connecting said members in a drill string, rollers journaled on one of said members and interrupted screw threads on the other member positioned for engagement with said rollers when said impact surfaces are separated and the members are in predetermined relative positions 10 of rotation with respect to each other, said threads having sufficient pitch to act upon said rollers to cause relative rotation between said members into jarring position in response to predetermined longitudinal stress between said 15 members.
